YIELDABLE PROPELLER

Filed Oct. 15, 1928

UNITED STATES PATENT OFFICE

SCOTT H. LILLY, OF TOLEDO, OHIO, ASSIGNOR, BY MESNE ASSIGNMENTS, TO ST. REGIS PAPER COMPANY, OF NEW YORK, N. Y., A CORPORATION OF NEW YORK

YIELDABLE PROPELLER

Application filed October 15, 1928. Serial No. 312,496.

This invention relates to a yieldable propeller and has for its object to provide a propeller with yielding blades which automatically adjust themselves so as to apply an approximately even pressure upon the material discharged, regardless of the rate of discharge.

The invention will be described as applied to a device similar to that disclosed in Patent No. 1,658,734, issued to Lewis D. Nelson February 7, 1928, for feeding material into valve bags, and is particularly adapted for feeding granular or pulverulent material.

In the accompanying drawings forming a part of this specification, Figure 1 shows a vertical section, on the line 1—1 of Figure 2, through a propeller embodying the invention, with a portion of a casing sufficient to indicate the relation of the propeller to the casing; Figure 2 is a plan view of the parts shown in Fig. 1; Fig. 3 is a fragmentary section on the line 3—3 of Fig. 1; Fig. 4 is a detail view showing a portion of a propeller blade.

In the construction shown, there is a casing 10 which may be of substantially cylindrical formation, having a bottom 11 and a discharge spout 12 at one side thereof adjacent the bottom. Immediately above the bottom 11 there is a disk 13 having a conical boss 14 around its center and mounted upon a vertical shaft 15, which may be driven in any desired manner. Attached to the upper surface of disk 13 there is a series of blades 16. The blades are shown mounted in grooves 17 formed in the upper portion of disk 13.

In the construction shown, the bottom 18 of the groove is formed so that there is a substantially continuous curve from the upper portion of boss 14 to the outer end of groove 17. The upper side of the groove 17 is narrowed towards the outer edge of the disk so as to leave overhanging lugs 19. A flange 20 is attached to the lower edge of each blade 16 and is adapted to fit into a groove 17, the flange being notched at 21 to receive lugs 19, and the shoulder 22 at the end of the notch 21 being adapted to rest against the inner end of lug 19.

Ordinarily the blades will be maintained in

position by centrifugal force and the friction of the material thereon, which both operate to crowd the blades outward to the limit allowed by shoulders 22 and lugs 19; but, if desired, the flange 20 may be provided with a hole 23 registering, when the blade is in position, with a hole 24 in the bottom of groove 17, and the blade may be secured in position by a screw 25 passing through the holes.

As will be seen most clearly from Fig. 3, the blade is normally curved so that the top 26 is advanced in the direction towards which the propeller revolves, as indicated by arrow 27. The blades are made of spring metal so that they will yield under pressure.

It will be readily understood that the material in casing 10 falls down by gravity into the path of the revolving blades. In the construction shown, the bottom of the blade is arranged radially of disk 13. The top 26 of the blade is parallel with the bottom of the blade, but since it is normally positioned in advance of the bottom, as indicated in Figs. 2 and 3, the top of the blade is at an angle to the radii of the disk which would pass through said top, and, therefore, has a tendency to crowd material outward away from the center of the disk. At the same time, the curvature of the blade acts to crowd material downward and prevent its return upward into the casing. The result is that material caught in front of a blade is forced downward and outward until it escapes in the direction of arrow 28 through outlet 12, as long as the blade maintains its normal position.

When the flow of material from the outlet is obstructed by the closure of gate 29, or for any other reason, the resistance encountered by the blades is increased so that the top of the blade is pressed backward nearer to the radial plane passing through the bottom of the blade. It will be readily seen that when the top of the blade is pressed backwards so far that the blade is vertical, the material is no longer pressed downward by the curved formation of the blade and the top of the blade is then radial so that it presses material forward, but not outward. There will still be some tendency to press the material outward because of centrifugal force, and when

the gate is closed, there may be a continued pressure which will bend the top of the blade even slightly back to the bottom thereof. In this case, the reverse condition from that first described results, so that the blade tends to press material inward and upward sufficiently to counterbalance the excess centrifugal force.

It will be readily seen from the above that 10 yieldable blades mounted in the described manner result in a continuous pressure on the material during the revolution of the propeller, which pressure is automatically maintained within a comparatively narrow range by the straightening of the blades when 15 resistance is encountered, and their return to normal position when resistance is lessened. In this way the feeding force exerted upon the material remains within comparatively 20 narrow limits regardless of the speed of discharge of material.

The number of blades may be varied as desired. In the construction shown, disk 13 is 25 grooved for six blades, with the blades such distance apart that at least one of them will be constantly forcing material towards the outlet passage.

For various reasons it is desirable to have 30 the discharge of a package-filling device as nearly constant and uniform as practicable. The construction of the blades is such that 35 they tend to exert a uniform pressure on the material, as discussed above, and the employment of a considerable number of blades tends to make the discharge more uniform during each revolution of the propeller.

In the construction shown, the blades are 40 illustrated as being of substantially as large size as can be fitted on the disk outside of the central cone. As will be seen from Fig. 1, the inner end of the upper edge 26 of the blade projects to the rear of the cone, as viewed in that figure, but it will be understood that when the blade is straightened up the upward 45 edge is raised sufficiently to escape being obstructed in its movement by the central cone.

It will be readily understood that a greater or less degree of curvature than that disclosed in the drawings, as well as a variation in the 50 number of blades utilized, may be made without departing from the principles of the invention. Furthermore, if desired, the shape of the blade may be otherwise varied.

At the right of Figures 1 and 2 there is 55 shown a blade 30 which has a top portion 31 extending approximately as far radially of the propeller as blades 16 but being comparatively narrow vertically and connected to the bottom flange by a shank 32. In this 60 case the blade is curved normally in the horizontal plane as well as in the vertical plane so that when it meets with resistance the twisting action of the free end of upper portion 31 will tend to straighten shank 32 both 65 vertically and horizontally.

At the lower left portion of Figure 2 there is shown a blade 33 similar to blade 16 except that the upper portion is no longer than the bottom thereof.

It will be readily understood that various 70 other modifications may be made in the shape of the blades, as well as in their number, within the scope of the appended claims.

What I claim is:

1. In apparatus of the character described, 75 an approximately cylindrical casing having a discharge outlet through the side thereof adjacent one end and a propeller mounted rotatably, substantially concentric with the casing, and in register with said opening, the propeller being provided with spring blades, 80 said blades being curved forward so that they normally tend to press material downward and are moved towards a vertical position by resistance of material.

2. In apparatus of the character described, 85 an approximately cylindrical casing having a discharge outlet through the side thereof adjacent one end and a propeller mounted rotatably, substantially concentric with the 90 casing, and in register with said opening, the propeller being provided with spring blades normally curved in a direction to force the material towards the end of the casing and outward therefrom but so that pressure 95 thereon will tend to straighten the blades towards a radial position.

3. In apparatus of the character described, 100 an approximately cylindrical casing having a discharge outlet through the side thereof adjacent one end and a propeller mounted rotatably, substantially concentric with the 105 casing, and in register with said opening, the propeller being provided with spring blades, 110 said blades being mounted on their edges towards the end of the casing and having said edges extend substantially radial of the propeller and the blades normally curving away from said edges and in the direction of rotation of the propeller.

4. In apparatus of the character described, 115 a casing having a substantially cylindrical portion with a substantially vertical axis and a lateral discharge opening adjacent the bottom thereof, and a propeller in the bottom 120 of the casing substantially concentric therewith and comprising a disk in the bottom of the casing and blades of resilient material upon the upper side of the disk, said blades being substantially in register with said discharge opening, having one edge held rigid 125 radially of the disk and being curved forward from said edge so as to normally tend to press material downward and be moved towards a vertical position by resistance of material.

5. In apparatus of the character described, 130 a rotatable propeller provided with a blade mounted adjacent its radially outer end and having a resilient portion extending from said outer end towards the axis of the pro-

- 5 peller, but normally in advance of said outer end in the direction of the rotation of the propeller, and free to move, in response to resistance by propelled material, to a position less advanced than said outer end.
- 6 5. In apparatus of the character described, a casing having a substantially cylindrical portion with a substantially vertical axis and a lateral discharge opening adjacent the bottom thereof, and a propeller in the bottom of the casing, substantially concentric therewith, and comprising a disk in the bottom of the casing and resilient blades upon the upper side of the disk, said blades being substantially in register with said discharge opening and having their bottoms extend substantially radial of the propeller, the curvature of the blades being such that the major portion of each blade is normally ahead of the bottoms thereof in the direction of rotation of the propeller.
- 7 6. In apparatus of the character described, a casing having a substantially cylindrical portion with a substantially vertical axis and a lateral discharge opening adjacent the bottom thereof, and a propeller in the bottom of the casing, substantially concentric therewith, and comprising a disk in the bottom of the casing, the disk having a hub portion rising from its upper side, the outer side of the hub portion being curved downward and outward and there being grooves in the upper surface of the disk, the bottoms of said grooves being substantially of a continuation of the curve of the outer surface of said hub and there being stop lugs in the upper outer portion of said grooves, and blades having flanges on their lower edges adapted to enter said grooves and abut against said lugs to position the blades.
- 8 7. In apparatus of the character described a casing having a substantially cylindrical portion with a substantially vertical axis and a lateral discharge opening adjacent the bottom thereof, and a propeller in the bottom of the casing, substantially concentric therewith, and comprising a disk in the bottom of the casing, the disk having a hub portion rising from its upper side, the outer side of the hub portion being curved downward and outward and there being grooves in the upper surface of the disk, the bottoms of said grooves being substantially a continuation of the curve of the outer surface of said hub and there being stop lugs in the upper outer portion of said grooves and blades having flanges on their lower edges adapted to enter said grooves and abut against said lugs to position the blades, said blades being made of spring material and the upper sides thereof being normally in advance of the side connected to said flanges.
- 9 8. In apparatus of the character described, a casing, and a propeller in the casing having a blade of spring material, said blade being mounted along a line substantially radial of the propeller and being normally curved away from said line of support forwardly in the direction of rotation of the propeller.
- 10 9. In apparatus of the character described, a rotatable propeller provided with a substantially radial blade, the portion of said blade nearest the axis of the propeller being resiliently movable circumferentially of the propeller with respect to the portion of the blade farther from the axis of the propeller, the first said portion being normally in its forward position with respect to the rotation of the propeller, but movable towards its rearward position by pressure of material being fed.
- 11 10. In apparatus of the character described, a substantially cylindrical casing having a radial discharge opening, and a propeller rotatable about an axis extending longitudinally of the casing, said propeller being in the radial plane of said opening and comprising a blade extending substantially radially but with its inner portion normally in advance of its outer portion, said blade being resiliently held in position and the inner portion being constructed to yield under pressure of propelled material a greater distance angularly of the propeller than the outer portion yields under like resistance.
- 12 11. In testimony whereof I have hereunto signed my name to this specification.
